US0D1036723S

(12) **United States Design Patent** (10) Patent No.: **US D1,036,723 S**
 (45) Date of Patent: ** Jul. 23, 2024

(54) **REAR LIGHT**

(71) Applicant: **Dr. Ing. h.c. F. Porsche Aktiengesellschaft**, Stuttgart (DE)

(72) Inventor: **Emiel Burki**, Stuttgart (DE)

(73) Assignee: **Dr. Ing. h.c. F. Porsche Aktiengesellschaft** (DE)

(**) Term: **15 Years**

(21) Appl. No.: **29/827,908**

(22) Filed: **Feb. 23, 2022**

(30) **Foreign Application Priority Data**

Aug. 24, 2021 (EM) 008660856-0003

(51) LOC (14) Cl. **26-06**

(52) U.S. Cl.

USPC **D26/28**

(58) **Field of Classification Search**

(57) **CLAIM**

The ornamental design for a rear light, as shown and described.

DESCRIPTION

FIG. 1 is a perspective view of a rear light showing my new design;

FIG. 2 is a rear view thereof;

FIG. 3 is a front view thereof;

FIG. 4 is a right side view thereof, the left side view being a mirror image thereof;

FIG. 5 is a top view thereof; and,

FIG. 6 is a bottom view thereof.

The broken lines illustrate portions of the rear light that form no part of the claimed design.

1 Claim, 6 Drawing Sheets
